ELECTRIC TRUCK

William Stuebing, Jr., Cincinnati, Ohio, assignor
to The Yale & Towne Manufacturing Com-
pany, Stamford, Conn., a corporation of Con-
necticut

Application August 19, 1930, Serial No. 476,325

20 Claims. (Cl. 254—2)

The invention relates to trucks that have a frame adapted to be raised or lowered in order that the truck may assume a load or deposit it. The present invention provides a practical and efficient truck which is economical in the use of electric power, and very easy to operate.

One object of the present invention is to permit the lowering of the lifting frame in apparatus of this general type without energizing the electric motor or other prime mover. Economy in the use of power is important in trucks of this character, not only on account of the cost of the power, but also because of the saving of time involved in changing batteries. Another object of the invention is to stop the lifting motor automatically once the load has been raised.

It is still another object of the invention to provide holding mechanism to hold the frame at its uppermost position independently of the position or condition of the lifting motor. The device for holding the frame in its upper position should operate automatically and the provision of a device of this character is another object of the invention.

In order that the operation of the vehicle may be a very simple matter a single actuation of a control should be all that is needed to either raise or lower the frame. The attainment of the above is therefore another object of the invention.

Still another object of the invention resides in the use of the weight of the frame, or of the load itself or of both to run the motor back to starting position, thus saving power.

Another object of the invention is greatly to reduce the possibility of breakage of gears or other parts of the frame moving mechanism. Lifting trucks of the type herein described are subject to very rough handling, and breakage of gears or other parts has not been uncommon. Other objects of the invention will be in part obvious or in part pointed out hereinafter.

The invention accordingly consists in the features of construction, combination of elements, and arrangements of parts as will be exemplified in the structure to be hereinafter described, and the scope of the application of which will be indicated in the appended claims.

In the accompanying drawings, in which is shown a preferred form of various possible embodiments of my invention:

Fig. 1 is a front elevation of a truck constructed in accordance with the invention.

Figs. 2 and 3 are respectively elevations of the left and the right hand sides of the truck, the

frame being shown in its lowest position in Fig. 2, and in its uppermost position in Fig. 3.

Fig. 4 is a view partly in plan and partly in section of the truck, the section being taken along the line 4—4 of Fig. 2.

Referring to Figs. 2, 3 and 4, the frame of the vehicle comprises a pair of longitudinal members 1, 1 which are held in spaced relation by a transverse frame member 2 and a rear wheel supporting member 3. At the front of the vehicle 10 the members 1, 1 are suitably connected to a differential housing 4, which contains the usual differential gearing and axle shafts for the front wheels 5, 5. The front wheels 5, 5 may be connected by universal joints, not shown, to the axle 15 shafts aforesaid, the wheel journals being mounted on vertical pivots 6, 6 in order that the vehicle may be steered. As this mechanism forms per se no part of my present invention, it need not be further described herein, particularly as 20 one way of accomplishing the foregoing is fully disclosed in U. S. Letters Patent No. 1,343,358 granted June 15, 1920, to George R. Fairchilds.

Referring to Fig. 4, the axles for the rear wheels 7, 7 are journaled in supports 7a, 7a which likewise are mounted upon vertical pivots 8, 8 in order that steering may be effected by the rear wheels as well as the front wheels. The front wheel supporting members 9, 9 provide rearwardly extending arms 10, 10 which are connected by a tie rod 11 in order that the front wheels may move in unison. Referring to the upper left hand corner of Figs. 1 and 2, said wheels are controlled by a steering arm 12 carried on the front of the vehicle; the steering arm is attached to the upper end of a vertical shaft 13, that is suitably supported by brackets 15, 15, the bottom of the shaft having fastened to it an arm 16 that is connected by means of a link 17 to a forwardly projecting arm 18 fastened to or formed integrally 40 with the left hand member 9.

In similar fashion, as best shown in Fig. 4, the supporting members 7a, 7a for the rear wheels 7, 7 are connected by a tie rod 19 which connects arms 20, 20 fastened to or integrally formed with said members so that the rear wheels will move in unison. The rear wheels 7, 7 are adapted to be directed by the steering arm 12 and to that end a long link 21 (Fig. 4) connects an arm 22 of one of the members 7a to a bell crank lever 23 which is pivotally mounted at 24 to the machine frame, the other free end of said bell crank lever being connected by means of a link 25 to the tie rod 11.

Referring now to the central portion of Figs. 55

2 and 3, a housing 26 for the lifting frame gearing is secured in any suitable manner to one of the longitudinal truck frame members 1, and a battery bed 27 is likewise supported by the longitudinal members 1, 1; as herein disclosed the supporting media comprise a strut 28 fastened to the casing 26, a strut 29 extending between said bed and a longitudinal member 1, and a strut 30 extending between the differential housing 3 and the battery bed. The box for the battery is indicated at 31, and the battery is readily removable therefrom for charging purposes.

Located beneath the forward end of the battery box 31 is a motor 32 which drives the vehicle 15 and which is energized by the battery 31, the driving pinion of the motor being connected to gearing, not shown, enclosed in a casing 33 attached to the differential housing 4. The final gear of this gear train meshes with the ring gear 20 of the differential gearing in the housing 4.

The operator controls the vehicle by means of a hand lever 34 and a foot pedal 35, both of which operate electrical control mechanism housed in a controller box 36 that is conveniently attached 25 to the front of the battery box 31. The arrangement of these two controlling devices is such that current can be supplied to the motor 32 only when the foot pedal 35 is down and a spring is provided to raise said pedal when the operator is 30 not actually stepping upon it. Secured to the battery box 31 are a pair of channel members 37, 37 and supported by means of these members is a platform 38 for the operator to stand upon, said platform being secured directly to a rod 39 35 that extends between the members.

Trucks of the type herein disclosed are used to move relatively heavy loads in warehouses, stations, or similar places where efficiency of operation and economy of time are prime requirements. The load is placed upon a skid or the like having supports spaced to permit the truck to pass between them. The bottom of this skid is just above the level of the truck platform when the latter is in its lowermost position. When 40 the frame of the truck is raised, the skid supports are lifted from the floor or ground. For speed of operation and to relieve the operator from heavy work it is desirable to raise the lifting frame by electric power, but the lowering of it by electric power serves no useful purpose and is 45 a waste of energy.

Referring to Figs. 2, 3 and 4, a lifting frame 40 is preferably connected to the frame of the vehicle by means of a parallel linkage mechanism. As best shown at the right hand side of Figs. 2 and 4, a pair of links 41, 41 are pivotally connected at 42, 42 to the rear of said frame, and at 43, 43 to the member 3. Another pair of links 44, 44 are connected to the frame 40 at the front 45 end thereof, and are pivotally connected at 45, 45 to the frame members 1, 1. The connection between the links 44 and the lifting frame 40 is preferably made by means of a cross rod 46 which is secured to said frame by means of brackets 47, 47, said cross rod 46 having other functions which 50 will be hereinafter indicated.

Indicated in the central portion of Figs. 2 and 3, is an electric motor 48 which operates the frame lifting mechanism, the casing of said motor 55 being suitably secured to the battery bed 27 as by means of a support 49. The motor 48 may of course be energized by the same battery that provides tractive power for the vehicle; attached to the front of the battery box 31 is a controller box 50 for the motor 48, and a controlling lever

51 adapted to be swung in a vertical plane projects from the box.

As best shown in Fig. 2, the controlling lever is pivotally mounted at 52 in the box 50; it has secured to it a latch member 53 which moves angularly with it. This latch member 53 cooperates with another latch member 54 that is pivotally mounted at 55 in the box 50, so that with the parts in the position shown in Fig. 2 the controller handle 51 cannot be raised until the latch 54 is depressed. Springs, not shown, are provided both to urge the latch 54 upwardly into latching position, and to raise the controller handle 51. When the said controller handle is raised, the circuit to the lifting motor 48 is opened, and when the controller is lowered to the position shown in Fig. 2, said circuit is closed, and the motor 48 is energized. It will be readily apparent that when the operator moves the handle 51 downwardly, the latch 54 will snap into position engaging the latch 53 and holding the controller handle in the position in which the motor 48 is energized until such time as the latch 54 is depressed either by the operator, or in a manner that will be herein-after described. It will be further apparent that when the controller handle 51 is thus released, it will move upwardly under the influence of the spring, not shown, thus de-energizing the motor 48.

Still referring to Fig. 2, the shaft 56 of the motor 48 has fastened to it a pinion gear 57 which meshes with a large gear 58 that is fastened to a shaft 59 that is suitably journaled in the casing 26. A pinion 60 is fastened to the shaft 59, and this pinion 60 meshes with a second large gear 61 that is fastened to a shaft 62 which is also journaled in the casing 26. It will be apparent that the foregoing constitutes reduction gearing to drive the shaft 62 at a very slow speed compared with that of the motor shaft 56.

Referring now particularly to Figs. 3 and 4, a crank 63 located on the outside of the reduction gear casing 26 is fastened to the shaft 62 and consequently revolves with it. This crank arm 63 has a crank pin 64 which may be formed integrally with it.

As best shown in the central part of Fig. 4, the transverse shaft 46 carries an arm 65 which is pivotally mounted thereon. In order to give more rigidity to the shaft 46 and in order to prevent the arm 65 from moving in any other manner than angularly about the axis of shaft 46, an additional bracket 66 is provided for the support of shaft 46, said bracket being fastened to the front of the platform 40 as are the brackets 47, 47, and said bracket having a slot for the reception of the arm 65. At the end of the arm 65 is a hook 67 which is adapted to fit over the pin 64 in a manner best illustrated by Fig. 3. The crank 63 revolves in a counter-clockwise direction, Fig. 2, or in a clockwise direction, Fig. 3, and as the arm 65 at all times rides upon the pin 64, it is apparent that the pin 64 will engage the hook 67 and draw said hook and the arm 65 with it. Such action will draw the shaft 46 to the left, Fig. 2, and the frame 40 will therefore ride upwardly upon the links 41 and 44.

In order to place as little stress as possible upon the motor 48 and the gearing in the casing 26, and in order to permit the platform 40 to be lowered without energizing the motor 48, I provide latching means to hold the platform 40 in its raised position. Pivotally mounted about one-third of the way up on the strut 29, and as best shown in Fig. 2, is a bell crank lever 68 having

a hook portion 69 at one end. The hook portion 69 will automatically fall into place behind the shaft 46 when the latter is raised, as the weight of the bell crank 68 urges it in a clockwise direction, Fig. 2. The bell crank lever is prevented from moving below the position in which it is shown in Fig. 2 by means of a suitable stop 71. The front portion of the hook 69 is so shaped that the shaft 46 has a lifting action upon it, in order 10 to lift the hook when they come into engagement. Thus the platform 40 will be automatically held in its uppermost position whenever it is raised by the motor 48 and the mechanism described.

15 In order to save electric current and to relieve the operator from the necessity of stopping the platform lifting motor 48, automatic mechanism is provided for that purpose; as shown in Figs. 1 and 2, the controlling lever latch 54 is connected by means of a rod 72 with a bell crank lever 73 that is pivotally mounted at 74 (see Fig. 2) underneath the front end of the battery bed 27; the other end of said bell crank lever 73 is connected by means of a rod 75 to a detent 76 20 pivotally connected at 77 to the transverse frame member 2. The upper end of the detent 76 is in the path of movement of the wrist pin 64 of the crank 63, and consequently when said pin engages said detent, the latter will be moved and 25 the latch 54 will be drawn downwardly by reason of the connections described. This will permit the controller lever 51 to move upwardly under the influence of the spring, not shown, and thus the motor 48 will be de-energized.

30 35 By reason of the provision of the hook 69, automatic stoppage of the platform elevating mechanism is not depended upon to hold it at its top position. The limited movement of the crank 63 after the hook 69 has engaged the rod 46 causes the crank pin 64 to move away from the hook 67, but the arm 65, resting directly upon the crank pin 64, maintains engagement with it and follows it down. It should be observed that during this time the motor is running without any 40 load and hence is using little current.

45 Referring to the left hand portion of Fig. 2, extending horizontally between the channel members 37 is a shaft 80 and said shaft has attached to it a treadle 81 and also an arm 82. The 50 arm 82 is connected by means of a rod 83 to the upper end of the bell crank lever 68. Downward movement of the treadle 81 raises the hook 69, and this releases the shaft 46 and the platform 40.

55 60 With the parts in the position shown in Fig. 3, it is clear that the load is taken entirely upon the links 41 and 44, and that the frame 40 will not start downwardly even though released, unless jarred in some way or otherwise given a slight movement to the left. Therefore, resilient means are provided to urge the frame to the left, Fig. 3, in order to start it upon its downward movement when the hook 69 is disengaged as already described.

65 70 As best shown in Figs. 3 and 4, mounted on the shaft 46 is a link 84 which connects the shaft 46 with one end of a lever 85 that is pivotally mounted at 86 on the transverse member 2. The lever 85 has an arm 87 which is connected at 88 to a cylinder 89 of a check device. A rod 90 projects from the other end of said check device and is pivotally fastened at 91 to a bracket 92 depending from the battery bed 27. This check device is not per se part of the present invention, and 75 may be of any suitable construction, such for ex-

ample as that disclosed in U. S. Letters Patent #1,279,481 granted September 17, 1918 to Wm. R. Stuebing, Jr. The check device of this patent has a spring which tends to draw the rod 90 into the cylinder 89, and therefore, since in this illustrative embodiment of the invention the rod 90 is shown as fastened to a stationary portion of the vehicle, said spring tends to raise the cylinder 89, and such action urges the platform 40 to the left as will be readily seen from Fig. 3. Consequently when the treadle 81 is depressed, and the hook 69 is raised, the platform 40 will be urged to the left by the aforesaid spring, and after the links 41 and 44 have left the vertical position, the platform will fall of its own weight, 15 being restrained from violent movement, however, by the check device of the above patent.

20 The mode of operation of the frame lifting mechanism and associated parts has already been indicated in the foregoing description, but will be briefly reviewed for a clear understanding of the invention. Assuming that the lifting frame is in the position shown in Fig. 2, which is its lowermost position, the operator, when he desires to raise it, will depress the controller lever 51 thus 25 energizing the motor 48, it being remembered that by means of the latches 53, 54, the motor energizing circuit is maintained. The crank 63 and crank pin 64 will thereupon commence to rotate in a counterclockwise direction, Fig. 2, and 30 the pin 64 will engage the hook 67 and thus start the frame 40 on its upward movement. When the pin 64 has moved substantially 180 degrees, the parts will be in the position shown in Fig. 3, the frame 40 being fully lifted, with the load supported directly upon the links 41 and 44, and with the hook 69 engaging the shaft 46 to hold said frame in the position of Fig. 3 against the tendency of the spring in the check device 89 to urge it to the left. The hook 69 drops automatically 35 into the position shown in Fig. 3, as already described.

40 45 The crank 63 and crank pin 64 keep on turning, the motor 48 being relieved of load, however; said crank pin finally engages the detent 76 and stops the motor. This terminates that portion of the operating cycle involved in raising the frame.

50 55 When the operator desires to lower the lifting frame, he steps upon the treadle 81, and thus raises the hook 69, and the spring in the check device 89 urges the frame 40 to the left. Thereafter, said frame descends by reason of its own weight and that of whatever load it supports, if any. The check devices in the cylinder 89 described in the patent to Stuebing referred to prevent rapid downward movement of the frame but do not greatly resist slow movement thereof. Therefore, when the hook 67 engages the pin 64, which had been stopped substantially at the detent 76, said hook draws said pin to turn the crank 63 in a counterclockwise direction, Fig. 2, and the weight of the frame is sufficient to revolve the moving part of the motor 48 and the various interposed gearing in the casing 26, restoring the parts to the position shown in Fig. 2. Such movement of the operating mechanism to initial position takes place without the use of any electric power.

60 65 70 It will be obvious that instead of using a spring in the check device 89 to impart the initial downward movement to the frame 40, and instead of using any spring at all, gravity might be used, in which case the links 41 and 44 would 75

not be quite vertical at the uppermost position of the frame.

It will be seen that if the vehicle collides with something, the frame 40 receiving the shock, this 5 simply momentarily urges the hook 67 away from the pin 64, and cannot in any manner injure the gearing in the casing 26 or the motor 48. It will be seen further that the apparatus is simple and practical, and can be operated by unskilled labor.

10 As many possible embodiments may be made of the above invention and as many changes might be made in the embodiment above set forth, it is to be understood that all matter hereinbefore set forth, or shown in the accompanying drawings, is to be interpreted as illustrative and not in a limiting sense.

I claim:

1. In a truck, a frame, a mounting for said frame on the truck permitting it to be raised and lowered, power means to raise the frame, latch means independent of said power means adapted to hold it in raised position, and means of connection between said power means and frame so inherently arranged that the continuous operation 25 of said power means will lift said platform only a pre-determined amount, said means of connection being constructed so that the power means cease lifting said frame through positional adjustment of said means of connection caused by continued operation of the power means.

2. In a truck, a frame, a mounting for said frame on the truck permitting it to be raised and lowered, power means to raise the frame, latch 30 means to hold it in raised position, and a disengageable connection between the power means and the frame to permit the frame to be lowered by disengaging the latch.

3. In a truck, a frame, a mounting for said frame on the truck permitting it to be raised and lowered, power means to raise the frame, and a disengageable crank and hook connection between the power means and the frame to raise the latter.

4. In a truck, a frame, a mounting for said frame on the truck permitting it to be raised and lowered, power means to raise the frame, a disengageable crank and hook connection between the power means and the frame to raise the latter, and a latch to hold the frame in raised position.

5. In a truck, a frame, a mounting for said frame on the truck permitting it to be raised and lowered, power means to raise the frame, means 55 forming a connection that is adapted to transmit a pull but not a thrust between the power means and the frame and is operable to submit said pull only until said frame has reached a predetermined elevated position regardless of the continuance of operation of said power means, said means of connection being constructed so that the power means cease lifting said frame through positional adjustment of said means of connection caused by continued operation of the power means.

6. In a truck, a frame, a mounting for said frame on the truck permitting it to be raised and lowered, an arm connected to the frame, a hook on the end of the arm, and a crank adapted to engage the hook to raise the frame

7. In apparatus as claimed in claim 6, the combination with the parts therein specified, of means to hold the frame at its upper position.

8. In apparatus as claimed in claim 6, the combination with the parts therein specified, of

means to stop the crank after the frame is raised.

9. In apparatus as claimed in claim 6, the combination with the parts therein specified, of means to hold the frame at its upper position, and means to stop the crank after the frame is raised.

10. In a truck, a frame, a mounting for said frame on the truck permitting it to be raised and lowered, a motor to raise the frame, connections between said motor and said frame having substantially a dead center position when the frame is raised, and means to position the parts beyond the aforesaid dead center position while maintaining the frame raised, in order that the weight of the frame may turn the motor when said frame is released.

11. In a truck, a frame, a mounting for said frame on the truck permitting it to be raised and lowered, power means to raise said frame, means connecting said power means to said frame where by operation of said power means will raise said frame to a predetermined position while permitting movement of said connecting means and power means beyond said predetermined position without further actuation of said frame, said means of connection being constructed so that the power means cease lifting said frame through positional adjustment of said means of connection caused by the continued operation of the power means, and means for maintaining said frame in its elevated position independently of said power means.

12. In a truck, a frame, a mounting for said frame on the truck permitting it to be raised and lowered, means effective to hold the frame at a predetermined elevated position when it has been elevated to that position, power and connecting means for elevating the frame to said predetermined position, said connecting means permitting over-running of said power means after the frame has been raised and secured in its elevated position, and means whereby the frame when released will operate through gravity to actuate the power and connecting means to their initial pre-lifting position.

13. In a truck, a frame, a mounting for said frame on the truck permitting it to be raised and lowered, detent means effective to hold the frame at a predetermined elevated position, an electric motor having means of connection for elevating said frame, said means permitting over-running of said motor relatively to said frame after the frame has been raised and secured in said predetermined position, said means of connection being arranged for retractive movement with said motor to initial position by said frame when it is released from its elevated position for downward gravitational movement.

14. In a truck, a frame, a mounting for said frame on the truck permitting it to be raised and lowered, power means to raise said frame, mechanical means of connection between said power means and frame so inherently arranged that continuous uninterrupted operation of said power means will elevate said frame only a pre-determined amount, said means of connection being constructed so that the power means become disconnected from and cease lifting said frame through positional adjustment of said means of connection caused by the continued operation of the power means.

15. In a truck, a frame, a mounting for said frame on the truck permitting it to be raised and lowered, power means to raise said frame, mechanical means of connection between said power

means and frame so inherently arranged that continuous uninterrupted operation of said power means will elevate said frame only a pre-determined amount, said means of connection being constructed so that the power means become disconnected from and cease lifting said frame through positional adjustment of said means of connection caused by the continued operation of the power means and means for shutting off said power upon completed movement of said frame.

16. In a truck, a frame, a mounting for said frame on the truck permitting it to be raised and lowered, power means to elevate said frame, means of connection between said power means and frame for elevating said frame, said means being constructed so that continuous operation of said power means will raise said frame to an elevated position, the continued movement of said power means being in itself effective to leave said platform in its elevated position while said power means continue operation.

17. In a truck, a frame, a mounting for said frame on the truck permitting it to be raised and lowered, power means to elevate said frame, means of connection between said power means and frame for elevating said frame, said means being constructed so that continuous operation of said power means will raise said frame to an elevated position, the continued movement of said power means being in itself effective to leave said platform in its elevated position while said power means continue operation, and switch mechanism for said power means operated by the continued operation of said power means.

18. In a truck, a frame, a mounting for said frame on the truck permitting it to be raised and lowered, detent means effective to hold the frame at a predetermined elevated position, said frame being movable downwardly through gravitation,

an electric motor having means of connection for elevating said frame, said means of connection being arranged for retractive movement with said motor to initial position by said frame when said frame is released from its elevated position for downward gravitational movement.

19. In a truck, an elevating frame, a mounting for said frame on the truck whereby it may be raised and lowered, an electric motor having means of connection for elevating said frame, said means of connection being inherently ineffective to lift said frame more than to a predetermined position regardless of the continued operation of said power means, detent means for holding said frame in elevated position and for releasing it for gravitational downward movement, and means whereby the connection between said frame and power means is reestablished by said downward gravitational movement of the frame.

20. In a truck, a frame, a mounting for said frame on the truck whereby it may be raised and lowered, an electric motor having means of connection for elevating said frame, said means of connection being inherently ineffective to lift said frame more than to a predetermined position regardless of the continued operation of said power means, and means of connection between said power means and frame so inherently arranged that continuous uninterrupted operation of said power means will elevate said frame only a pre-determined amount, detent means for holding said frame in elevated position and for releasing it for gravitational downward movement, and means whereby the connection between said frame and power means is reestablished by said downward gravitational movement of the frame.

WILLIAM STUEBING, JR.
